United States Patent Office

Des. 186,328
Patented Oct. 13, 1959

186,328

TONGS

Douglas F. Holland, Toronto, Ontario, Canada

Application June 1, 1959, Serial No. 56,166

Term of patent 3½ years

(Cl. D44—4)

Fig. 1 is an edge view of the tongs showing my new design;

Fig. 2 is a side elevation thereof; and

Fig. 3 is a perspective view of the tongs.

I claim:

The ornamental design for tongs, as shown.
